UNITED STATES PATENT OFFICE.

JOSEPH S. DUNCAN, OF CHICAGO, ILLINOIS, ASSIGNOR TO ADDRESSOGRAPH COMPANY, OF CHICAGO, ILLINOIS, A CORPORATION OF ILLINOIS.

EJECTOR FOR PRINTING-MACHINES.

1,353,899.

Specification of Letters Patent. Patented Sept. 28, 1920.

Application filed June 23, 1919. Serial No. 306,029.

To all whom it may concern:

Be it known that I, JOSEPH S. DUNCAN, a citizen of the United States, residing at Chicago, in the county of Cook and State 5 of Illinois, have invented certain new and useful Improvements in Ejectors for Printing-Machines, of which the following is a specification.

The object of this invention is to provide 10 an addressing machine with ejector mechanism of simple construction for automatically ejecting the work at the conclusion of the printing operation.

The invention is particularly adapted for 15 hand operated addressing machines which are largely employed for addressing envelopes, cards, tags and other work, and I have illustrated the invention embodied in such a machine in the accompanying drawings, but 20 I do not wish to be understood as limiting the scope of the invention to this particular application since it is apparent that it may be embodied in other types of printing machines for operation in the manner hereinafter set forth.

A further object of the invention is to 25 provide a mechanism which can be bodily attached to and removed from the machine by means of a single screw without in any 30 way affecting the normal operation of the machine.

In the drawings—

Figure 1 is a plan view showing my invention applied to a hand-operated addressing machine with the parts in printing position;

Fig. 2 is a side elevation of the ejector or throw-off attachment as shown in Fig. 1;

Fig. 3 is a rear elevation of the attachment as shown in Figs. 1 and 2 and showing a portion of the addressing machine;

Fig. 4 is a sectional view on the line 4—4 of Fig. 3;

Fig. 5 is a detail sectional view showing 45 the normal position of the tripper and its associated parts;

Fig. 6 is a detail view showing the normal position of the pawl 45 in its relation to the parts immediately associated therewith.

Referring to the drawings, the machine comprises a suitable base 4 having a work support 5, an ink ribbon 6, a magazine 7 in which the printing devices (not shown)

are stored and from which they are fed by 55 suitable means forwardly on the tracks 8 to printing position at the ribbon 6 and below the platen which is carried by the impression member 9 pivotally mounted at 10, 10, to the base and provided with an 60 operating handle 11. The impression member is normally held in elevated position by a spring 10' connected with said member and to the base of the machine. In this type of machine the printing devices are 65 fed forward from the magazine one at a time to printing position below the ink ribbon, the envelops or other work are fed by hand one at a time to printing position above the ink ribbon, the impression member 70 is operated by hand to press the envelop upon the ink ribbon against the printing device to obtain the impression, the impression member is automatically returned by its spring or other suitable means to 75 elevated position, the printing device which has been printed is fed forward from printing position, unless duplication is desired, and another printing device is fed into printing position, and the ribbon is automatically fed at each operation of the machine.

A fixed guide 12 extends across the base of the machine, as shown in Fig. 1, and is provided with arms 13 which are adjustably 85 secured in a suitable manner in projections 14 on the base. This guide is arranged to be engaged by the upper edge of the work and it is adjusted to the size of the envelop or other work as may be required to register 90 and guide the work for the printing operation.

The ejector comprises an angular member having a horizontal portion 15 to lie beneath the envelop and an upright portion 95 16 to form a guide or registering device for one end of the envelop. This ejector is mounted on one end of a rod 17 which has a flattened upper surface 17' and is slidably supported in an opening 18 in the frame 19 100 of the ejector mechanism and also in an opening in the plate 20 which is carried by a rod 21 adjustably mounted in said ejector frame and secured in position by the set screw 22. A horizontally swinging lever 23 105 is pivotally mounted on the upright pin 24 secured in the frame of the ejector mechanism (Figs. 2, 3) and the forward end of

this lever is pivotally connected at 25 to one end of a link 26. The other end of this link is pivotally connected by a clamp screw 27 to the ejector supporting rod 17 (Fig. 1).
5 The ejector is adapted to travel in a direction transverse of the machine and it and its actuating lever 23 are limited in their return movement by a stop 28 on the frame 19, there being a cushion 29 on the face of the
10 stop to relieve the parts of shocks and jars. The pivot end of the lever 23 is provided with an angular projection 30, (Fig. 4) and a spring 31 fastened at one end to the end of this projection and at its other end to the
15 frame 19 returns the ejector and its operating lever to normal position against the cushion 29, as shown in Fig. 1.

The means for setting the ejector or throw-off mechanism for operation and for operating the ejector lever 23 comprise a rocker pivoted at 32 to the ejector frame and having the oppositely disposed arms 33, 34 (Figs. 1, 3). The arm 33 has a downward projection 35 at its outer end which is arranged in the path of a tripper 36 carried by the impression member. A square pin 37 is also carried by the arm 33 (Figs. 1, 4) and is located between the pivot of the rocker and the projection 35. A latch device in the form of a spring-pressed pawl 38 is pivotally mounted at 39 in an angular position on the ejector frame. In normal position, with the impression member elevated, the tripper will push the latch pawl against its spring and hold the free end away from pin 37, as shown in Fig. 5. When the impression member is depressed the tripper is carried away from the latch pawl and spring 40 presses the latch pawl against the
35 pin 37 until this pin, being carried forward with the rocker arm 33 by engagement of the tripper with projection 35 on said rocker arm, is moved beyond the end of the latch pawl, whereupon the latch pawl is swung
40 by pressure of its spring to the position shown in Fig. 4. In this position the flat end of the latch pawl is opposed to the flat face of the pin 37 and when the impression member begins its return travel the rocker
45 spring 42 will swing the rocker until pin 37 engages the end of the latch pawl which then holds the rocker in set position for operating the ejector while the tripper travels with the impression member away from projection 35. There is a slight lost motion of the rocker and its pin 37 with relation to the latch pawl at the end of the impression stroke of the impression member, as shown in Fig. 4, which avoids a fine adjustment of
55 parts and allows for work of different thicknesses and for adjustments of the platen.
60 A projection or arm in the form of a plate or bar 41 is fastened on the end of rocker arm 34 (Figs. 1, 2) and a strong spring 42 is fastened at one end to a lug 43 on the

ejector frame and at its other end to a pin 44 on the rocker arm 34. An operating pawl 45 (Figs. 1, 4) is pivoted at 46 between its ends in ears 47 on the ejector lever 23. A spring 48 interposed between the pawl 45
70 and the ejector lever 23 normally pushes the outer beveled end 45' of said pawl outward adjacent the bar 41 (Fig. 6). When the rocker is swung to the position shown in Fig. 1, by the downward impression movement of the impression member, the bar 41 is carried rearward beyond the operating pawl 45 to clear the same (Fig. 4), whereupon the spring 48 pushes the pawl 45 outward until the beveled end thereof is arranged in the path of the bar 41 on the return movement of the latter. The bar 41 is carried rearward somewhat beyond the end 45' of the bar, (Fig. 4) so that when the rocker is released by the operation of the tripper on the return movement of the impression member the rocker will be entirely free for an instant and the strong spring 42 will give to the rocker and to the bar 41 carried thereby, a quick and vigorous swinging action before the bar strikes the pawl. This will result in the bar striking the pawl forcibly and imparting to the ejector lever and the ejector a desired quick ejecting movement. An adjusting screw 49 bearing
80 against lever 23 positions the pawl 45 for engagement with bar 41.
90

A lug 50 on the rocker is arranged to engage a lug 51 on the ejector frame to limit the return movement of the rocker (Fig. 1) and a flat spring 52 is arranged on the ejector frame to be engaged by the ejector lever to limit the forward movement thereof.

The entire ejecting mechanism is mounted on the ejector frame 19 and is detachably secured to the base of the machine by a single screw 53.

My invention will be readily understood from the foregoing description in connection with the drawings. On each downward impression movement of the impression member the ejecting mechanism is set for operation and at the limit of the upward return movement of the impression member the tripper 38 is released to permit the ejector mechanism to operate. The ejector has a very quick movement, both forward and return, and it will eject the envelop or other work at one side of the machine so that another envelop may be arranged in printing position and the impression operation conducted rapidly.

An important feature of my invention is that the operation of the ejector is not in any way affected by a variation in the speed of operation of the impression member either on its impression movement or on its return movement. It will be noted that the ejector mechanism is set or "cocked" on the desired movement of the impression mem- 130

ber, when the tripper swings the rocker to the position indicated in Fig. 4 which permits the latch pawl 38 to swing into said position in front of the pin 37. This takes place during every full downward movement of the impression member whether this movement be fast or slow. And the operation of the ejector occurs on the return movement of the impression member when 10 the tripper releases the latch device 38 from engagement with the pin 37, whether this return movement be fast or slow. The importance of operating the ejector with uniformity whether the impression member is 15 operated fast or slow will be readily appreciated because these machines may be operated by unskilled boys and girls who do not always regard uniformity of operation as essential to the work. But it is essential 20 that the ejector should, at every operation, properly perform its complete function of throwing out the envelop to a receptacle or to a position at one side of the machine and this must be done with uniformity regard- 25 less of the speed of operation of the impression member. My invention performs its function in a manner which will be apparent from the foregoing description and drawings and as above stated the throwing out 30 operation takes place quickly and uniformly near the completion of the stock of the impression member.

I am aware that some changes in the form, proportion and arrangement of parts will 35 probably have to be made to adapt the invention to other machines of different kinds and sizes, and that other such changes may be required or desirable for various reasons and I would therefore have it understood 40 that I reserve the right to make all such changes as fairly fall within the scope of the accompanying claims.

I claim:

1. In a printing machine, the combination 45 of an ejector, a lever to operate said ejector, a spring controlled rocker, means interposed between the rocker and said lever for communicating movement of said rocker in one direction to said lever, means for holding 50 the rocker in set position for operating the lever, and a tripper for operating said holding means.

2. In a printing machine, the combination 55 of an ejector, a lever to operate said ejector, a spring controlled rocker pivotally mounted independent of said lever and movable conjointly therewith and independently thereof, means for holding the rocker in set position for operating the lever, and a tripper 60 per for operating said means.

3. In a printing machine, the combination 65 of an ejector, a lever to operate said ejector, a spring controlled rocker, means for communicating movement of the rocker in one direction to the lever, means for holding

the rocker in set position, and a tripper for moving said rocker to set position and for releasing the holding means.

4. In a printing machine, the combination 70 of an ejector, a lever to operate said ejector, a spring controlled rocker, means for communicating movement of the rocker in one direction to the lever, a latch pawl for holding the rocker in set position, and a tripper engaging said rocker on its move- 75 ment in one direction to move the rocker to set position and engaging the holding means on its movement in the return direction for releasing said means.

5. In a printing machine, the combination 80 of an ejector, a lever to operate said ejector, a spring controlled rocker, yielding means carried by the lever and adapted to be arranged in the path of travel of the rocker in one direction for operating said lever, 85 means for holding the rocker in set position, and a tripper for moving the rocker to set position and for releasing the holding means.

6. In a printing machine, the combination 90 of an ejector, a lever to operate said ejector, a rocker, a spring for moving the rocker in one direction to operate the ejector lever, yielding means for holding the rocker in set position for operation, and a tripper carried by a spring actuated impression member and 95 adapted to engage said rocker to set the same and to release said holding means.

7. In a printing machine, the combination 100 of an ejector, a lever to operate said ejector, a spring controlled rocker pivotally mounted independent of said lever, means for communicating movement of the rocker in one direction to the lever, a tripper carried by a spring actuated impression member and 105 adapted to move the rocker to set position, and means for holding the rocker temporarily in set position and adapted to be operated by the tripper to release the rocker.

8. In a printing machine, the combination 110 of an ejector, a lever to operate said ejector, a spring controlled rocker comprising two oppositely disposed arms, means coöperating with one of said arms for communicating movement of the rocker in one direction to the lever, means coöperating with the 115 other arm for holding the rocker in set position, and a tripper coöperating with said other arm to move the rocker to set position and adapted to engage said holding means to release the same.

9. In a printing machine, the combination 120 of an ejector, a lever to operate said ejector, a spring controlled rocker, means for communicating movement of the rocker in one direction to the lever, a pin on the rocker, 125 a tripper arranged to engage said pin to hold the rocker in set position, and a tripper for moving the rocker to set position and for releasing said holding means.

10. In a printing machine, the combina- 130

tion of an ejector, a lever to operate said ejector, a spring controlled rocker, means for communicating movement of the rocker in one direction to the lever, a pin on the 5 rocker, a yielding latch device adapted to be arranged in the path of said pin to hold the rocker in set position, and a tripper for releasing said latch device.

11. In a printing machine, the combination of an ejector, a lever to operate said 10 ejector, a spring controlled rocker, means for communicating movement of the rocker in one direction to the lever, a pin on the rocker, a yielding latch device adapted to be arranged in the path of said pin to hold the 15 rocker in set position, and a tripper carried by an impression member and engaging said rocker in its movement in one direction to set the rocker in operation and engaging 20 said latch device on its movement in the reverse direction to release said device.

12. In a printing machine, the combination of an ejector, a lever to operate said 25 ejector, a spring controlled rocker, means for communicating movement of the rocker in one direction to the lever, a pin on the rocker, a latch device arranged to engage 30 said pin to hold the rocker in set position, and a tripper carried by an impression member and engaging the rocker on its impression 35 movement to move the rocker to set position and engaging the holding means to release said means near the end of its return movement from the impression operation to enable said rocker to operate the ejector.

13. In a printing machine, the combination of an ejector, a lever to operate said 40 ejector, a spring controlled rocker comprising two oppositely disposed arms, means cooperating with one of said arms to communicate movement of the rocker in one direction to the lever, a pin and a projection on the other arm, yielding means for engaging 45 said pin to hold the rocker in set position,

and a tripper carried by an impression member to engage said projection and move the rocker to set position and adapted to release said holding means.

14. In a printing machine, the combination of an ejector, a lever to operate said 50 ejector, a rocker, a spring for swinging said rocker in one direction, a pawl adapted to be arranged in the path of said rocker to communicate movement of the rocker to the 55 ejector lever, means for holding the rocker in set position, and a tripper carried by an impression member and adapted to move said rocker to set position and to release said holding means. 60

15. In a printing machine, the combination of an ejector, a lever to operate said 65 ejector, a spring controlled rocker having two oppositely disposed arms, a bar on one arm, a yielding pawl carried by the lever and adapted to be arranged in the path of 70 said bar to communicate movement of the rocker to the lever, means for holding the rocker in set position, and a tripper adapted to move the rocker to set position and to release said holding means.

16. In a printing machine, the combination of an ejector, a lever to operate said 75 ejector, a spring to return said lever to normal position, a two arm rocker mounted independently of said lever, a bar on one of said arms, a device on the lever adapted to be arranged in the path of said bar to communicate movement of the rocker in one direction to the lever and to clear the bar on 80 the return movement of the lever, a spring for swinging said rocker in one direction, means for holding the rocker in set position, and a tripper for moving the rocker to set 85 position and for releasing said holding means.

JOSEPH S. DUNCAN.
